(57) **CLAIM**

The ornamental design for a car, toy car replica and/or other replica as shown and described.

DESCRIPTION

FIG. 1 is a front perspective view of the car, toy car replica and/or other replica showing my design;

FIG. 2 is a front view thereof;

FIG. 3 is a right-side view thereof;

FIG. 4 is a rear view thereof;

FIG. 5 is a left-side view thereof; and,

FIG. 6 is a top plan view thereof.

The broken lines depict portions of a car, toy car replica and/or other replica, which form no part of the claimed design.

1 Claim, 6 Drawing Sheets
